CLAIM

The ornamental design for a rear gunsight, substantially as shown and described.

DESCRIPTION

FIG. 1 is a perspective view of the rear gunsight of the present invention.

FIG. 2 is a side view of the rear gunsight of the present invention.

FIG. 3 is a plan view of the rear gunsight of the present invention.

FIG. 4 is a rear view of the rear gunsight of the present invention.

FIG. 5 is a front view of the gunsight of the present invention.

FIG. 6 is a bottom view of the rear gunsight of the present invention.

The undisclosed side of the gunsight is substantially the same in appearance as the side of the gunsight shown in FIG. 2.

FIG. 1.

FIG. 2.

FIG. 3.

FIG. 4.

FIG. 5.

FIG. 6.
